UNITED STATES PATENT OFFICE

109,057

DESIGN FOR AN EXAMINING TABLE

William R. Enochs, Indianapolis, Ind.

Application January 19, 1938, Serial No. 74,402

Term of patent 3½ years

To all whom it may concern:

Be it known that William R. Enochs, a citizen of the United States, residing at Indianapolis, in the county of Marion and State of Indiana, has invented a new, original, and ornamental Design for Examining Tables, of which the following is a specification, reference being had to the accompanying drawings forming a part thereof.

Fig. 1 is a front perspective view of an examining table in closed position embodying my new design;

Fig. 2 is a similar view thereof with the table in open position;

Fig. 3 is a fragmentary sectional view on the line 3—3 of Fig. 1;

Fig. 4 is a fragmentary sectional view thereof on the line 4—4 of Fig. 1;

Fig. 5 is a rear perspective view of the table shown in Fig. 1;

Fig. 6 is a fragmentary sectional view on the line 6—6 of Fig. 5;

Fig. 7 is a fragmentary sectional view thereof on the line 1—1 of Fig. 5;

Fig. 8 is a front elevational view on an enlarged scale of one of the drawer pulls as shown in Fig. 1 on each of the three drawers there appearing, and centrally through which pulls, the section line 4—4 extends; and

Fig. 9 is a sectional view thereof on the line 9—9 of Fig. 8, including a fragment of the table wall.

The shading on the front and rear sides of the table represents a contrasting color appearance in natural wood effects together with differently directed lines of the wood grain.

I claim:

The ornamental design for an examining table, as shown and described.

WILLIAM R. ENOCHS.
